UNITED STATES PATENT OFFICE.

SERGE HERINGFEL AND FÉNELON DUBREUCQ, OF CHARENTON, FRANCE; SAID DUBREUCQ ASSIGNOR TO SAID HERINGFEL.

MACHINE FOR GRINDING TOOLS AND FOR SIMILAR PURPOSES.

1,377,684.

Specification of Letters Patent. Patented May 10, 1921.

Application filed March 28, 1919. Serial No. 285,880.

To all whom it may concern:

Be it known that we, SERGE HERINGFEL, civil engineer, a citizen of the Republic of France, residing at 3 Avenue de la Liberté, 5 Charenton, Seine, France, and FÉNELON DUBREUCQ, foreman, a citizen of the Republic of France, residing at 3 Avenue de la Liberté, Charenton, Seine, France, have invented new and useful Improvements in 10 and Relating to Machines for Grinding Tools and for Similar Purposes, of which the following is a specification.

The invention relates to that particular class of machine for grinding standard 15 tools, which is equipped with appliances for adjusting the tool in all planes or positions relative to the grinding wheel.

Broadly speaking, the novelty of the herein-described machine resides in that the 20 relative movements between the grinding wheel and the tool are automatic. The invention consists essentially in the herein-after described contrivances by the aid of which the above mentioned result is 25 achieved. Another feature of the invention consists in that the machine is fitted with an arrangement which permits, without trials, the immediate grinding of standard tools such as are in current use. Another 30 feature of the invention consists in a reproducing cam device whose profile can be made as desired so as to allow of grinding tools of varying forms and profiles, including milling cutters, boring cutters and 35 even drilling tools.

Two types of the machine have been designed, Model No. I which is suitable for mechanical work-shops in which the work comprises the machining of parts of small 40 or medium dimensions and Model II which is very much more powerful and is designed for the machining of large parts and for removing large masses of metal.

The machine consists essentially of the 45 following parts:—

A. A frame.

B. A system of carriages having longitudinal and traversing movements actuated either automatically or by hand as desired.

50 C. A system of members constituting the automatic movements for actuating the carriages and apparatus on which are fixed the tools to be ground.

D. An abutment and positive index mech-

anism for the instantaneous positioning, 55 without any preliminary of certain standard tools.

Figures 1 to 21 inclusive show the first type.

Figs. 22 to 25 show the second type. 60

First type.

10 **FIRST TYPE, (Figs. 1 to 21.)***Frame and carriages, (Figs. 1, 2, 3 and 4.)*

A. The frame consists of a dish-shaped table 1 mounted on a cast-iron standard 2. 15 On the table 1 is fixed a grinding-wheel holder in two parts 3, 4. The part 3 is fixed by means of bolts to the table 1; the upper part of the holder comprises two sleeves, one of which receives the shaft 24 carrying the pulleys 5 and 6 of the transmission mechanism, the pulley 7 driving the shaft carrying the grinding-wheel 54 and the pulley for driving the pump, while the other receives the shaft 10 upon which the 20 grinding wheel is mounted. The part 3 forms a pivot for the movable arm 4 and consequently for the grinding wheel holder.

The portion 4 or movable arm which carries the grinding wheel holder can be regulated as to height by means of the regulating screw 8. The movement is obtained as follows:—One of the branches 4^a of the movable arm is provided with a lug 4^b the end of which moves in a circular guide 3^b which is concentric with the horizontal axis of pivot 3 and is fixed on one of the arms of said pivot. The screw 8 is mounted in a screw threaded boss 3^a of the other branch of the pivot support 3 and acts through its 30 end on an extension 4^c of the second branch of the movable arm 4. It is obvious that by turning screw 8 in a direction in which a thrust is exerted, the extension 4^c and consequently the arm 4 are pushed upwardly, 35 by turning screw 8 in opposite direction, the movable arm 4 turns downwardly by the action of gravity. A lock nut (Figs. 1 and 2) permits the fixing of the oscillating arm 4 when the grinding wheel is at the 40 required height.

The shaft 10 rotates in bearings 11 which are fitted into conical seats. In order to permit of rapidly changing the grinding-wheel 54, the end of the corresponding shaft 55 is provided with a screwed mandrel 12 which can be locked or released by hand.

B. The system of carriages consists of three parts:—

The pivoting support 13 which, by means 60 of the scale 16 and the fixed reference mark 17 allows of positioning both the longitudinal and transverse carriage according to the angle required in the horizontal plane. The whole can be fixed in place by means of the 65 nut 18.

The transverse carriage 14 is actuated by means of a screw in the same way as the carriage of an ordinary lathe. The movement of this carriage for moving it toward or away from the wheel 54 can be obtained, 70 as desired, either by hand by means of the crank 19 or automatically by means of a ratchet mechanism, as will be explained below.

The longitudinal carriage 15 can slide 75 freely to the extent of its entire length in both directions. It can be actuated by means of a lever 21, when it is desired to work it by hand; it can also be given an automatic reciprocating movement by means of a device described below.

A groove formed in the side of the longitudinal carriage 15 enables abutments 23 to be fitted so as to limit its stroke if necessary.

The device for holding the tool 66 to be ground is placed upon this longitudinal carriage 15.

C. *Automatic movements.*

The mechanism for transmitting the automatic movements is mounted in a gear-case 20 placed on a prolongation of the shaft 24.

The automatic movements are three in 95 number. They are effected through the medium of flexible shafts.

(1) Automatic reciprocating movement of the longitudinal carriage 15 and consequently automatic movement of the tool in 100 front of the grinding wheel 54, which produces the operation of grinding proper. This movement is utilized when the grinding device is used with abutment and positive index marks and, in general, for grinding tools having a current profile.

(2) Automatic progressive advance of the transverse carriage 14 and consequently of the tool 66 toward the wheel 54 until the necessary amount of metal has been removed from the cutting edge of the tool.

(3) Oscillatory movement of the plate carrying the reproducing cam. This movement is utilized when using the device for grinding tools having special profiles.

(1) *Automatic reciprocating movement of the longitudinal carriage 15, (Figs. 5 to 10.)*

This movement originates at 26. At the 120 end of the shaft 24 is fixed a worm-wheel 28 having on one side teeth 29 which can engage with similar teeth on a sleeve 29^a which receives at 26, a flexible shaft 26^a (Figs. 1 to 4). In the upper portion of the cover 125 of the gear-case 20 is formed a slot 30 through which projects the coupling-lever 31 which pivots about the shaft 32, and is provided with a handle 34 (Fig. 5).

If the parts are as shown in the drawing 130

(Fig. 5), that is to say disengaged, if it is desired to couple up, one need only press upon the knob 33 of the lever in such a manner as to cause the stop 36 to leave the notch 35 and throw the lever whereupon the stop 5 will fall into the notch 37. At this moment, the jaws of the sleeve 29^a are in engagement with those of the wheel 29; the flexible shaft 26^a therefore rotates at the same speed as the shaft 24.

Figs. 2, 9 and 10.

On the carriage 14, Fig. 2, is fixed a casing 38 which contains a worm 39. This latter drives a wheel 40 carrying a shaft 41 on the end of which is fitted a crank 42 having a pin 43 which receives the driving rod 22 at its other end by means of a pivot pin 44 to the table of the longitudinal carriage 15 (Fig. 2). The flexible shaft 26^a being connected to the shaft of the worm 39, (Fig. 10), the rotation of this latter causes the crank 42 to rotate and, through the intermediary of the connecting rod 22, imparts a reciprocating motion to the carriage 15.

(2) Progressive advance of the transverse carriage 14.

The mechanism for putting the movement into gear is located in the same casing 20 as that which contains the coupling mechanism for the carriage 15. Coupling and uncoupling are effected by means of the lower lever 46 (Figs. 1 and 5.) The latter is held in one or the other of the notches 47 or 48. The effect of these movements is to move the wheel 45 toward or away from the worm 28, thus effecting coupling and uncoupling respectively of the flexible shaft 25^a (Figs. 1 to 4) starting at 25, as shown in Fig. 6.

Figs. 7 and 8.

At the extremity of the carriage 14 and mounted on the screw for advancing this carriage, is arranged a ratchet-mechanism. This mechanism, which is capable of a slight sliding movement in the direction of the carriage, owing to its being mounted on two pins on the extremity of the carriage, comprises a spindle 49 having at one end an eccentric stud 49^a which spindle receives at the one end the flexible shaft 25^a and at the other a pawl 50 fitted on the stud 49^a. Owing to the said eccentric stud 49^a, the pawl 50 is given an oscillating motion which causes it to act on a ratchet wheel 51 and to impart to this latter and consequently to the worm 52 and the wheel 53 an intermittent rotation, the effect of which is to produce a very slow advancing movement of the transverse carriage 14.

The extremity of the screw 55 (Fig. 8) which actuates the carriage 14 is of conical form, 65 as is also the bore of the wheel 53. In order

to obtain automatic movement of the carriage 14, the nut 56 is screwed up, the effect of which is to jam the wheel 53 upon the end of the screw 55 and thus insure the movement of the latter.

When it is desired to actuate the carriage 14 by hand, the nut 56 is slackened back and then the crank 19 (Fig. 1) is manipulated.

During the course of an operation, it is not necessary to slack back the nut 56 in order to stop the advance of the carriage; if the pawl is raised by hand, this will interrupt the movement and enable the tool 66 to be examined or calibrated, if necessary.

(3) Oscillating movement of the plate 85, 80 (Figs. 2, 5, 6, 14, 15, 16.)

The automatic drive is assured through the same lever 46 which effects the automatic advance of the carriage 14. The flexible shaft 27^a (Fig. 2) is attached to the end 27 of the shaft carrying the wheel 45 and terminates at the connection 64 on the extremity of the shaft 87 of the crank 86. A connecting rod 88 is connected to the pin 92 of this crank and the other end is connected to the plate 85. The rotation of the flexible shaft 27^a therefore imparts an oscillating motion to this plate, that is to say the grinding movement of the tool 66 95 against the wheel 54.

DESCRIPTION OF THE GRINDING APPARATUS PROPER.

These apparatus in which the tools to be ground are fixed are of two kinds:

(1) Apparatus provided with positive abutments and index marks.

This apparatus is used for the grinding of certain types of tools in general use. It can also be used for the grinding of all tools having simple profiles, whether straight or curved, in general use in workshops.

(2) Apparatus using a reproducing cam.

This apparatus is used for the grinding of tools having any profile desired, the profile of the cam being determined accordingly.

The two apparatus only differ in certain elements; they have the following parts in common, Figs. 11 to 16:—

A pivoting support 57 in the form of a right-angle which can turn in a horizontal plane about a bolt 58. Its circular soleplate 60, Fig. 11, carries a scale 59 on its entire periphery relative to a fixed mark 61 and allows of its positioning in all positions necessary for grinding. In the vertical rounded portion of the support 57 are fixed, on the one side, the central sleeve 62 carrying an arm 64, and on the other side, a sleeve 63. These sleeves 62 and 63 can pivot about a horizontal axis and can assume an inclined 120 125 130 135 140 145 150 155 160 165 170 175 180 185 190 195 200 205 210 215 220 225 230 235 240 245 250 255 260 position determined by the scale 65 marked upon the circular periphery of the top of the support 57.

5 *Apparatus having positive abutments and positive index marks, (Figs. 11, 12, 13 and 19, 20, 21).*

This is mounted in the sleeve 62 and comprises three parts:

- 10 (1) the tiltable plate 67.
 (2) the clamp 68 for holding the tool 66.
 (3) the guiding shaft 69, Fig. 13, supporting the plate 67.

15 (1) The inner face of the plate 67 is provided on the portion 70 near the edge with index apertures 71 (Fig. 12), whose positions correspond exactly to the angles of inclination 72 of the edges of the tools relative to the body thereof. The angular positions 20 corresponding to the different types of tools to be ground are immediately obtained without any preliminary adjustment by means of a pin 83 which can fall into one of the apertures 71. The upper portion of the plate 25 carries a boss to which the clamp or tool-holder 68 can be fixed.

The clamp or tool-holder 68 can pivot about an axis 68^a in such a manner as to allow of obtaining the inclination corresponding to the lateral clearance of the cutting edge of the tool.

30 A scale 74 formed on the circular edge of the tool holder 68 permits of verifying the exact angular corresponding position of 35 the tool 66. The desired position can be determined instantaneously and without preliminary adjustment by means of the pin 83' which falls into one aperture of the circular portion 67' of the plate 67 which 40 corresponds to the inclination required for grinding.

The tool is held in place by means of two clamping screws 77. Finally, the washer 81 keeps the whole in place in the sleeve 62.

45 (3) The grinding shaft 69 of the plate 67 is bored from end to end to receive a rod 78 which holds the abutment 78^b for determining the height which the tool is to have in its grinding position.

50 A spring 78^a surrounding said rod tends to push the abutment 78^b constantly away from the plate 67, *i. e.*, from left to right.

The rod terminates in a milled knob 79 provided with a stop pin 80. The knob 79 permits of disengaging the abutment at the right-hand end of the rod 78 from the edge of the tool, as soon as this latter is at the desired height. Disengagement having been effected, the knob is rotated in such a manner as to bring the stop-pin 80 on the boss 81', which prevents any return of the abutment into contact with the grinding wheel during the operation.

The sleeve 63 forms a housing for the 65 stop-pin 83 of the plate 67, which holds the

tools for each of the positions determined by the apertures 71. This pin is constantly pressed toward these apertures by a spring 82. In order to rotate the plate, it is sufficient to pull on the knob 84 when the point 70 of the pin is disengaged from its aperture and the plate 67 is free.

Figs. 14 to 18: Apparatus with a reproducing cam for grinding tools of varying profiles.

75 The support for this device is the same as for the apparatus having abutment and positive index marks. It is enough to remove the guiding shaft 69 and the stop-pin 83 and to replace them by a cam plate 85 and a roll-holding bracket 76.

80 On the plate 85 (Fig. 16) is mounted a cam 90. This cam has a profile which corresponds to that of the tool 66^a to be ground. The plate is thrust against an abutment roll 85 91 by the spring 89. If an oscillating motion in the directions of the arrows f', f², Fig. 15, is imparted to the plate, the tool 66^a is given an advancing and retreating movement relative to the wheel 54, in accordance 90 with the recesses or projections of the cam 90 and in consequence a grinding of the tool to the shape of the cam.

95 In order to obtain this movement automatically, the crank 86 is placed in the sleeve 95 of arm 64, this crank having a crank-pin 92 which receives the driving rod 88, Fig. 15, (see also Fig. 1) connecting the pin 92 to another pin 93 fixed on the plate 85. As the end of the shaft 27 is connected by 100 flexible shaft 27^a to the shaft 94, the motion is transmitted to the crank 86 which causes the desired oscillation to take place. It will be understood that it is possible with this apparatus to grind the face of a tool to any desired profile, all that is necessary being to 105 mount on the plate the corresponding cam.

SECOND MODEL, (Figs. 22 to 25.)

The principle is the same as that of Model 110 I in so far as the tool 66 to be ground can be positioned in all directions and at all angles, and in that devices with fixed index marks, positive abutments and stop-pins permit of 115 obtaining instantaneously and without preliminary adjustment or fumbling the exact position which the tool must have, according to its shape and profile. But the construction of the machine has had to be modified in order to insure the necessary rigidity and 120 strength of the different parts in view of the large cross-section of the tools to be ground and the heavy cuts made by the large grinding-wheel used.

125 The grinding-wheel 54 always remains at the same height and it is the table 1 carrying the longitudinal carriage 15 and the transverse carriage 14 which can be raised or lowered by means of a screw driven by a hand-wheel. The movements of the car- 130

riages are also effected by screws actuated by hand-wheels. The preliminary movement of the tool-holder toward the wheel is first effected by the hand-wheel 20^a. Thereafter, during the operation of the machine, the progressive advance of the tool 66 to be ground is effected by the movement of the upper portion of the support 57 of the tool-holder.

10 This advance can be obtained as in the case of Model I, either by means of the hand-wheel 19 or automatically by means of a pawl and ratchet mechanism identical with that of Model I. In this latter case the movement is transmitted by a flexible shaft fitted at 25 (Fig. 25) and coupling and uncoupling are effected exactly as in the case of the first type of machine.

In view of the great mass of the carriages and tool-holders, these latter, apart from the very slow progressive movement of the tool 66 toward the wheel 54, remain stationary during the work of grinding and the wheel itself is given a reciprocating movement relative to the tool. This motion is obtained through the intermediary of a shaft *a* (Fig. 22) on which is fixed a set of three stepped eccentrics or cams *b*. The wheel-holding carriage *c* which can slide on the frame *d* of the machine has a downwardly extending arm *f*, the central portion *g* (Fig. 25) of which forms an abutment for the eccentrics or cams *b*, while the lower portion *h* serves as a guide for the wheel-holding carriage.

15 The rotation of the shaft *a* and, consequently, of the cams *b* pushes the arm *f* of the carriage; the opposing spring *j* (Fig. 25) brings the carriage back to its original position, the result being an uninterrupted reciprocating movement of the wheel-holding carriage relative to the tool.

20 The steps of the eccentric or cam *b* permit of varying the extent of movement of the wheel 54 in accordance with the length of the portion to be ground. Passage from one cam to another is effected by means of the lever *k*.

The support 57 is fork-shaped so as to receive the trunnions *l* of the tool-holder 62 (Fig. 24). The entire support 57 can rotate about an axis *m*, the angular position being determined positively by a stop-pin 83^a, as in the case of Model I. In the same way, the tool-holder 62 can turn about these trunnions *l*; finally, the tool-holding bar 68 can itself turn in the sleeve, the corresponding angular positions being determined positively by the stop-pins.

25 Although the preceding description refers more particularly to the devices shown in the accompanying drawings, it will be understood that the invention applies to similar devices grouped either differently or in the same way on a grinding machine of larger or smaller dimensions, according to

the work to be done, but fulfilling the same conditions in general as the machine described. In this way, Figs. 22 to 25 show a more powerful machine than that described in the first place, but it nevertheless comprises the same essential devices from the point of view of the original characteristics of the invention.

In view of the power of this machine, which is suitable for grinding tools of large dimensions and designed to remove large masses of metal, the arrangement of the tables or carriages on which the tool-holder is mounted is different from that of the smaller machine. But, as is the case with this latter, the positions of the tool in all directions are still determined in a rapid manner and without preliminary trial by means of positive index marks, in which the stop-pins engage, either as regards the rotation of the tool about the axis of the sleeve in which it is fixed, or as regards the rotation of the tool-holder about a vertical axis, etc. Finally, the progressive movement of the tool toward the wheel is also obtained automatically by the same means as those employed in the case of the machine described in the first place.

Claims:

1. A machine for grinding tools comprising the combination with a fixed frame, of a grinding wheel mounted thereon, a support pivotally mounted on said frame, a carriage transversely movable on said support, a second carriage longitudinally slidable on said transverse carriage, said support having graduations thereon movable relatively to an index mark on the frame whereby the angular movement of said support and carriages may be readily determined, a tool holder mounted on said longitudinal carriage, means for reciprocating the longitudinal carriage and consequently the tool holder carried thereby relative to the grinding wheel, and mechanism for advancing the transverse carriage and consequently the tool holder toward the grinding wheel.

2. A machine for grinding tools comprising the combination with a fixed frame, of a grinding wheel mounted thereon, a transverse movable carriage having a longitudinally movable carriage slidably mounted thereon, means for automatically reciprocating said longitudinal carriage and mechanism including ratchet devices automatically actuated for gradually moving said transverse carriage toward the grinding wheel.

3. A machine for grinding tools comprising the combination with a fixed frame, of a grinding wheel mounted thereon, a transverse movable carriage having a longitudinal movable carriage slidably mounted thereon, means for reciprocating said longitudinal carriage, an actuating shaft for said

- transverse carriage, mechanism adapted to automatically actuate said transverse carriage toward the grinding wheel, means for disconnecting said mechanism from said actuating shaft and manually actuated means to move said transverse carriage toward or away from said grinding wheel.
4. A machine for grinding tools comprising in combination with a grinding wheel, 10 a shaft for driving said wheel, a transversely movable carriage having a longitudinally movable carriage slidably mounted thereon, means for automatically reciprocating said longitudinally movable carriage, and mechanism for automatically advancing said transversely movable carriage toward said grinding wheel, said means and mechanism being operated by said shaft.
5. In a grinding machine, the combination 20 with a grinding wheel, of carriages movable respectively transversely and longitudinally of the said wheel, a tool holding device mounted on the longitudinally movable carriage, means for automatically advancing said transverse carriage toward the grinding wheel, mechanism for automatically oscillating said tool holding device, and a shaft for simultaneously actuating said means and mechanism.
6. In a grinding machine, the combination 30 with a grinding wheel, of carriages movable respectively transversely and longitudinally of the said wheel, a tool holding device mounted in the longitudinally movable carriage, means for automatically advancing said transversely movable carriage toward the grinding wheel, mechanism for automatically oscillating said tool holding device, a shaft for simultaneously actuating 40 said means and mechanism, said means including clutch devices adapted to be readily manipulated for temporarily interrupting the driving connection between said shaft and said means.
7. In a grinding machine, the combination 45 with a grinding wheel, of carriages movable respectively transversely and longitudinally of the said wheel, a composite head pivotally supported on said longitudinally movable carriage for angular adjustment in a horizontal plane, a plate having a shaft extension mounted in said head and capable of angular adjustment about a horizontal axis, said plate having a plurality of apertures 50 formed therein, a spring-pressed pin slidably supported in said head for engaging said apertures and thereby determining the angular position of the plate, a tool holder pivotally mounted on said plate, means for 55 determining the correct position of the tool holder relatively to said plate and mecha-

nism for clamping the tool holder in adjusted position.

8. A machine for grinding tools, comprising in combination a grinding wheel, a tool holder, means for positioning said tool holder about three axes mutually perpendicular, an automatic means for reciprocating said tool holder relatively to the grinding wheel and means for moving said tool holder transversely thereto.

9. In a grinding machine, the combination with a grinding wheel, of a composite head movable as a unit longitudinally and transversely relatively to the grinding wheel 75 and capable of angular adjustment as a unit about a vertical axis, a plate pivotally mounted in said head so as to be adjustable about horizontal and vertical axes and a tool holder pivotally mounted on said plate 80 for angular adjustment relatively thereto.

10. In a grinding machine, the combination with a grinding wheel, of a composite head, a plate carried by said head and adjustable therein about two axes disposed at 85 right angles, a tool holder mounted on said plate for angular adjustment relatively thereto, clamping means associated with said holder for clamping the tool in desired vertical position, and a rod slidably mounted 90 in said head for indicating the proper vertical position of the tool.

11. In a grinding machine, the combination with a grinding wheel, of a composite head, a plate carried by said head and adjustable therein about two axes disposed at 95 right angles, a tool holder mounted on said plate for angular adjustment relatively thereto, clamping means associated with said holder for clamping the tool in desired 100 vertical position, a rod slidably mounted on said head, a spring tending to project the rod toward the grinding wheel for indicating the proper vertical position of the tool and means for normally maintaining said 105 rod in retracted position.

12. In a grinding machine, the combination with a grinding wheel, of a head adapted to receive a tool holding plate, a shaft capable of angular adjustment therein 110 and a stop-pin for determining the amount of said adjustment for grinding tools of simple profile, said tool holding plate and pin being replaceable by a tool holding plate and shaft adapted to oscillate in said 115 head and a roll holding bracket, respectively, said oscillatory plate having a removable cam thereon adapted to coat with said roller for imparting to the tool a profile corresponding to the cam.
